UNITED STATES PATENT OFFICE

JAMES RILEY SCHMIDT, OF TRENTON, NEW JERSEY, ASSIGNOR TO NEW JERSEY SEATING CO., OF NEW YORK, N. Y., A CORPORATION OF NEW JERSEY

DESIGN FOR A COMBINATION CHAIR SEAT AND BACK

Application filed September 10, 1929. Serial No. 32,715. Term of patent 14 years.

To all whom it may concern:

Be it known that I, JAMES RILEY SCHMIDT, a citizen of the United States, and a resident of Trenton, in the county of Mercer and State of New Jersey, have invented a new, original, and ornamental Design for Combination Chair Seat and Back, of which the following is a specification, reference being had to the accompanying drawing, forming part

In the drawing—

Figure 1 is a side elevation of a combination chair seat and back, showing my new design;

Figure 2 is a bottom plan thereof; and

Figure 3 is a rear elevation thereof.

I claim:

The ornamental design for a combination chair seat and back, as shown.

JAMES RILEY SCHMIDT.
